TYPEWRITING MACHINE

William J. O'Neil, New York, N. Y., assignor to
Underwood Corporation, New York, N. Y., a cor-
poration of Delaware

Application June 29, 1950, Serial No. 10,841

Term of patent 14 years

(Cl. D64—11)

To all whom it may concern:

Be it known that I, William J. O'Neil, a citizen of the United States, residing at New York, in the county of New York and State of New York, have invented a new, original, and ornamental Design for a Typewriting Machine, of which the following is a specification, reference being had to the accompanying drawings, forming part thereof.

Figure 1 is a front perspective view of a type-
writing machine, showing my design from the
right-hand side thereof.

Figure 2 is a rear perspective view of the type-
writing machine shown in Figure 1, the view being
from the left-hand side thereof.

It is to be understood that the keyboard shown

fragmentarily in broken lines is to be carried
over the space adjacent thereto and provided for
the same.

I claim:

The ornamental design for a typewriting ma-
chine, as shown and described.

WILLIAM J. O'NEIL.
